UNITED STATES PATENT OFFICE.

HENRY H. VAUGHAN, OF WESTMOUNT, AND RICHARD WEBB BURNETT, OF MONTREAL,
QUEBEC, CANADA.

CARLINE.

1,173,133.

Specification of Letters Patent. Patented Feb. 22, 1916.

Application filed January 17, 1914. Serial No. 812,731.

To all whom it may concern:

Be it known that we, HENRY H. VAUGHAN, of the city of Westmount, Province of Quebec, Dominion of Canada, and RICHARD WEBB BURNETT, of the city of Montreal, in the Province of Quebec, Dominion of Canada, both citizens of the United States of America, have invented certain new and useful Improvements in Carlines; and we do hereby declare that the following is a full, clear, and exact description thereof.

This invention relates more particularly to carlines of the type built up of angle-irons and the like, and has for its object to produce a carline or other arched structural member from mutually reinforcing angle-iron, and adapted to accommodate the roof purlins.

A further object is to produce a carline of minimum weight for required strength.

The invention may be said briefly to consist of a carline of channel cross-section composed of mutually reinforcing angle-irons tapered to their ends and depressed between their middle and ends to accommodate the purlins and present an arched effect.

For full comprehension, however, of our invention reference must be had to the accompanying drawings forming a part of this specification, in which similar reference characters indicate the same parts, and wherein:

Figure 1 is a transverse sectional view of a roof and illustrating our improved carline in side elevation; Figs. 2 and 3 are transverse vertical sectional views of the carline taken on line A A and B B Fig. 1 drawn to a larger scale; Fig. 4 is a plan view of the improved carline partly in section.

In the construction of our improved carline a pair of angle-irons *b* and *c* have their vertical flanges tapered near their ends as at *b'* and *c'* and overlapped throughout their full length. The angle-irons are first bent to present arched formation, and the upper angle-iron is depressed from the middle to its ends as at *d*, and the end portions thereof coincide with the upper edge of the tapered end of the lower angle-iron while the arched formation of the upper member is greater than the lower in order to increase the width

or depth of the carline at the middle for the purpose of increasing the concavity of the depressions. These depressions afford accommodation for the purlins in order that the roof will have the required drainage effect. The angle-irons thus formed are riveted or otherwise rigidly secured together with their upper and lower flanges extending on the same side of the carline to present channel cross-section and the tapered end portions of the lower edge of the vertical flange of the upper member resting in tight contact with the horizontal flange of the lower member, and the upper tapered edge of the vertical flange of the lower member in juxtaposition with the upper edge of the vertical flange of the upper member. This construction secures a mutual reinforcement of the carline-members owing to the fact that they are rigidly united in overlapping relation throughout their length, and owing to the bearing of the vertical flanges of the upper angle-iron on the horizontal flanges of the lower angle-iron near their ends the load exerted on the upper angle-iron is transmitted directly to the lower member, the effect being that provision is made for accommodating the purlins and the construction of a properly drained roof.

What we claim is as follows:

1. A carline of channel cross-section consisting of a pair of overlapping rigidly connected angle-iron members both arched, the upper to a greater extent than the lower, the end portions of the free edges of the vertical flanges of the said members being tapered.

2. A carline of channel cross-section consisting of a pair of overlapping rigidly connected angle-iron members both arched, the upper to a greater extent than the lower, the upper member being depressed between its middle and ends, the end portions of the free edges of the vertical flanges of the said members being tapered.

3. A carline of channel cross-section consisting of a pair of overlapping rigidly connected angle-iron members both arched, the upper to a greater extent than the lower, the upper member being depressed between its middle and ends, the end portions of

the free edges of the vertical flanges of the said members being tapered, and the said members being disposed with the edge of the vertical flange of one member in bearing relation with the horizontal flange of the other member.

5 In testimony whereof we have signed our

names to this specification in the presence of two witnesses.

HENRY H. VAUGHAN.

RICHARD WEBB BURNETT.
